(57) **CLAIM**

The ornamental design for a display screen with animated graphical user interface, as shown and described.

DESCRIPTION

FIG. 1 is the first image in a sequence for a display screen with animated graphical user interface showing my new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof; and,

FIG. 14 is the fourteenth image thereof.

The dot-dash lines in the figure illustrate the bounds of the claim. The dash-dash broken line showing of a display device illustrates environment. The remaining broken lines illustrate portions of the display screen with animated graphical user interface. The broken lines form no part of the claimed design.

1 Claim, 14 Drawing Sheets
